FOUR-WHEELED CART

Karl O. Larson, St. Paul, Minn.

Application February 14, 1957, Serial No. 44,875

Term of patent 7 years

(Cl. D14—3)

FIG. 1

FIG. 3

FIG. 2

FIG. 4

Figure 1 is a top plan view of a four-wheeled cart showing my new design.

Figure 2 is a side elevational view thereof.

Figure 3 is a side elevational view of my cart directly opposite to that illustrated in Figure 2.

Figure 4 is an end view thereof.

I claim:

The ornamental design for a four-wheeled cart, as shown and described.
